(57) **CLAIM**

We claim the ornamental design for a television system, as shown and described.

DESCRIPTION

FIG. 1 is a front perspective view of a television system, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a rear perspective view thereof; and,

FIG. 8 is an exploded, perspective view thereof.

The broken lines in the drawings depict portions of the television system that form no part of the claimed design.

1 Claim, 6 Drawing Sheets
